UNITED STATES PATENT OFFICE.

GEORGE E. SCHULTZ, OF PROVIDENCE, RHODE ISLAND, ASSIGNOR TO FRANK A. SAYLES, OF PROVIDENCE, RHODE ISLAND.

METHOD FOR CRAPING FABRIC.

1,076,608.

Specification of Letters Patent.

Patented Oct. 21, 1913.

Application filed March 24, 1913. Serial No. 756,360.

To all whom it may concern:

Be it known that I, GEORGE E. SCHULTZ, of Providence, in the county of Providence and State of Rhode Island, have invented a certain new and useful Method for Craping Fabric, of which the following is a specification, reference being had to the accompanying drawings, forming part thereof.

This invention has reference to an improved method for treating textile fabric to produce a permanent crape effect.

The main object of this invention is to take any suitable textile fabric and so treat the same while in the broad that the filling or warp threads thereof or both are caused to untwist to a large degree and the fibers of said threads to swell and open whereby said fabric is reduced in dimensions and the distorted threads or fibers produce the effect ordinarily known as crape.

Another object of the invention is to continuously treat fabric to produce the crape effect.

The invention consists in the method of continuously treating fabric hereinafter described and pointed out in the claims.

Figure 1, represents a side view of the machine for treating fabric to produce a crape effect. Fig. 2, represents a diagrammatic view illustrating steps in the improved method.

Similar reference characters designate corresponding parts throughout.

Textile fabric used in the making of crape finish or effect known as serpentine crape has a filling certain or all the threads of which in their process of manufacture have been given a twist which twist has been fixed by the application to the threads of a starchy fluid and the drying thereof. In fabrics more especially adapted for cross crape effect both the warp and filling or certain proportionate parts thereof have been formed from such twisted and starched threads. Heretofore it has been customary to subject said fabric to impregnation of a comparatively weak (2%) solution of caustic soda by coiling the fabric, in rope form, in a chamber, sometimes mounted for rotation, and then supplying to such chamber the solution of caustic soda. Among other objections to such method is the fact that the twisted fabric, in rope form, did not readily

absorb the solution and that such method was not continuous.

In carrying my improved method into practice I take the fabric in the broad and feed or move said fabric along continuously over a sustaining guide whereby said fabric is sustained in the broad and while it is so sustained and, preferably, moving in the direction of its length, I subject said fabric to the action of comparatively a strong solution of caustic soda at a suitable temperature. The solution referred to is in the nature of a detergent and is applied to the fabric in fine streams from a large number of spray pipes or other spraying devices so that such streams of solution are directed against both sides of the fabric so that all of the threads of the fabric are impregnated with the solution whereby the starchy coating of the threads is dissolved and washed away and the fibers of said threads are saturated with the solution and, as a result thereof, the fibers of the threads swell and the strands thereof untwist thus effecting the shortening or shrinking of said threads so that the dimensions of the fabric are reduced and the threads are distorted to produce the crape effect. During such untwisting and shrinkage of the threads and the consequent reduction in width of the fabric, the fabric tends to twist and form a rope which facilitates the feeding forward of the fabric through the usual guide eyes to subsequent operations.

The drawings forming part hereof illustrate the preferred form of machine for carrying out my improved method and in such drawings 5 indicates a suitable vat or tank having located thereabove the chamber 6 open at the top and bottom and provided with the upper guide 7 and with the series of spray pipes or spraying devices 8, 8 adapted to direct streams or sprays of fluid toward the central plane of said chamber 6.

Rotatably mounted in the tank or vat 5 is one or more fabric agitating devices 9, 9 square in cross section by which the fabric, in rope form, passing thereover is loosened without stretching the fabric. Such tank or vat 5 is also preferably furnished with the compartment 10 which is supplied with practically fresh water and said compartment 10 has the traveler fabric

carrying belt or device 11 adapted to carry forward the fabric, without stretching the same, toward the squeeze rolls 12, 12 adapted to squeeze from the fabric passing there-through a portion of the water carried by the fabric to this point.

The operation of the machine readily will be understood by reference to the drawings. The fabric is led over the guide 7, by which 10 the fabric is sustained in the broad, so called, or flat. From the guide 7 the fabric *a—a* is led through the chamber 6 and then over the agitators 9, 9 into compartment 10 and between the squeeze rolls 12, 12. When 15 now the solution above referred to, or any suitable solution, is supplied to the spraying devices 8, 8 under pressure, the streams of such fluid impinge against and, to some extent, penetrate the fabric *a—a* whereby during 20 the comparatively slow progression of the fabric through chamber 6 said fabric is thoroughly impregnated with such fluid, the adhesive or coating of the filling or warp threads or of all of said threads is dissolved 25 or loosened and to a large extent washed away and the fibers of said threads receive the solution. Gradually, as the fabric moves downward, the absorption of said solution by the filling threads becomes sufficient 30 to effect the swelling of the fibers thereof and their consequent retraction or shrinkage as well as the unwinding of their twist whereby the warp threads are drawn together and distorted to such an extent that the contraction thereof produces irregular 35 corrugations, crimps or wrinkles in the fabric. As such fabric, at a point distant from the guide 7 is free to twist the weight of the saturating fluid carried by the fabric 40 and the shrinking of the threads tends to contract the fabric into rope form and in such rope form the fabric is led over one or more of the agitators 9, 9 whereby the folds of the fabric are loosened and the fluid carried by the fabric penetrates more readily 45 into the fibers. After leaving the agitators 9, 9 the fabric *a—a* passes to the conveyer 11 in the compartment 10 of vat 5 and is passed through the comparatively 50 fresh water in said compartment. Finally the fabric is led between the squeeze rolls 12, 12 whereby a large portion of the water is squeezed from the fabric.

This improved method is not hereby restricted to the operation on fabric of any specific construction adapted to produce crape effects by or through its saturation. For instance the fabric adapted for this purpose may have certain or all of its filling

threads or of its warp threads or of both 60 thereof of any well known nature, construction or material adapted to shrink, unwind or become distorted in the operation herein described.

Apparently the manner of suspending the 65 fabric in the broad at one point while having the depending portion free to draw on said suspended portion, with the added weight of the saturating fluid, is of importance as the weight of said fluid tends to 70 draw downward the progressively saturated portions of the fabric and the tendency of said fabric is to contract.

Having thus described my invention I claim as new and desire to secure by Letters Patent—

1. That method of treating fabric to produce crape effects therein, which consists in sustaining suitable fabric in the broad at one point and permitting other portions of 80 the fabric to hang free, and subjecting said fabric while in the broad to the action of an alkaline saturating fluid.

2. That method of treating fabric to produce crape effects therein which consists in 85 sustaining fabric in the broad, progressively feeding said fabric, and progressively saturating the fabric while distended or in the broad with a solution of caustic soda.

3. That method of treating fabric to produce crape effects therein which consists in progressively feeding forward the fabric in the broad to distend the same applying to said fabric while distended a saturating detergent fluid under pressure and permitting 95 the saturated portion of said fabric to contract and draw on itself.

4. That method of treating fabric to produce crape effects therein which consists in feeding forward a suitable fabric, distending said fabric, subjecting the distended portion of the fabric to a saturating fluid applied under pressure, and agitating said saturated fabric.

5. That method of treating fabric to produce crape effects which consists in providing a multiplicity of cross streams of detergent fluid under pressure carrying forward the fabric to be treated in the broad in a direction at an angle to the direction of said 110 streams, straining said fabric by the weight of fluid taken by said fabric from said streams, and washing said fabric.

GEORGE E. SCHULTZ.
